UNITED STATES PATENT OFFICE.

MAX VON RECKLINGHAUSEN, OF NEW YORK, N. Y., ASSIGNOR TO THE R. U. V. COMPANY, INC., OF NEW YORK, N. Y., A CORPORATION OF NEW YORK.

APPARATUS FOR STERILIZATION OF FLUIDS BY ULTRA-VIOLET RAYS.

1,193,209.

Specification of Letters Patent.

Patented Aug. 1, 1916.

Application filed March 14, 1914. Serial No. 824,655.

To all whom it may concern:

Be it known that I, MAX VON RECKLINGHAUSEN, a subject of the Emperor of Germany, residing at New York, in the county and State of New York, have invented certain new and useful Improvements in Apparatus for Sterilization of Fluids by Ultra-Violet Rays, of which the following is a full, clear, and exact description.

10 In the process of sterilizing water and other fluids by exposure to ultra-violet rays, it has been found that greatly improved results are obtained if the fluid be exposed to the action of the rays while in the form of a thin sheet or film, and the object of the invention which forms the subject of this application is primarily the production of a sterilizing apparatus by the use of which the fluid is presented to the ultra-violet rays 20 while in this condition.

The invention also embodies a means for starting the lamp into action in an apparatus of this particular kind, when its construction or mode of use precludes its 25 proper movement for this purpose, independently of the apparatus, and other features of improvement useful in devices of this kind.

To these ends the invention consists of a 30 vessel or receptacle for containing the source of the rays, having corrugated walls over and down which the water is permitted to trickle or flow in a thin film or sheet through the zone of the rays, into a lower part of 35 the receptacle in which, if so desired, one or both ends of the lamp may be supported, so as to be immersed in and cooled by the fluid.

The invention also comprises a vessel or 40 receptacle of the kind described, supported on pivotal bearings, so that it may be turned through a certain angle, and by such movement bring the contained lamp into a position in which the mercury completes a metallic circuit between the two terminals.

Another feature of the invention consists 45 in mounting the vessel or receptacle on pivotal bearings and providing for it an

outlet or overflow opening through which it is emptied of its contents after use or 50 before being started into operation.

Another feature of the invention involves the provision of means for automatically regulating the rate of flow of fluid through the receptacle, and finally, the invention involves an attachment, by the operation of 55 which fluid will flow through the apparatus only when the lamp is in operation.

These several features of invention are illustrated in the accompanying drawings 60 in which—

Figure 1 is a central vertical section of the preferred form of apparatus. Fig. 2 is a top plan view of the apparatus shown in Fig. 1. Fig. 3 is an enlarged sectional view of the 65 upper portion of the receptacle.

Similar letters of reference indicate corresponding parts in the several figures.

When the vessel or receptacle in which the sterilization takes place is one in which 70 the lamp may not be inserted or withdrawn at pleasure it is necessary to provide for the tilting of the apparatus itself in order that the lamp may be started in operation, and the device is shown as one of this general 75 character.

In Fig. 1, A'' is a receptacle of any suitable material and B the source of ultra-violet rays in the form of a substantially straight tube with depending portions extending 80 downward to near the bottom of the said receptacle. This lamp is supported in any suitable manner in the receptacle and is not readily removable therefrom. The receptacle is of any suitable configuration, 85 that shown in the drawing being circular in general outline, and its walls are provided with corrugations indicated by E. The upper portion of the receptacle contains a receiver of any suitable design into which the 90 fluid to be sterilized is discharged and from which it overflows on to the corrugated walls. The receptacle A'' is supported by an enlarged base A' mounted by pivotal bearings H in a supporting bracket J, and the lamp 95 B, which, as above described, is a tube bent

back upon itself and the whole, bent into U-form, projects into the receptacle from below, its ends passing through the base A'.

The device is held normally in a vertical position by means of a catch L which, when released, permits it to be turned until the mercury flowing from the terminal chambers into the main tube completes a metallic circuit between the two terminals and at the same time lowers an outlet M to a point where the contents of the receptacle can escape. To permit the free movement of the entire receptacle, the pipe or duct, by which the fluid is led into the apparatus, should have a pivotal connection therewith coincident with the axis of the device.

The base A' of the main receptacle contains a perforated or open discharge chamber from which leads an outlet M, and these parts are so constructed that a certain amount of fluid sufficient to cool the electrode chambers of the lamp will accumulate in the base A'.

In practice I prefer to maintain the device in its operative position by means of an electro-magnet O in the lamp circuit. This magnet, when energized, may maintain the latch or catch L closed, but when not influenced by current will allow the catch to swing and drop the pivoted receptacle. In this way, as soon as the circuit through the lamp is interrupted the receptacle swings on its pivots and is automatically drained of the fluid which may be in the base A'.

It is important that the film of water descending over the corrugations E shall not be too thick, and that a ready but simple means for regulating the flow should therefore be at hand. To accomplish this I employ in the cap or upper portion of the receptacle a nozzle or spout P for delivering the fluid, which is vertically adjustable about its pivotal connection with the inlet pipe. The orifice of this spout is directed toward the opening R of a path for fluid around the apparatus, and if the flow from the spout is too abundant, a portion of the fluid will be carried off through this path. By the adjustment of the spout the amount of fluid which it can deliver into the receptacle will thus be readily determined.

The construction of the described apparatus may be greatly varied without departure from the invention, and the ways and means shown for accomplishing the result specified may be widely modified.

What I claim is:

1. An apparatus for sterilizing fluids by exposure to ultra-violet rays, comprising in combination a source of ultra-violet rays, a pivoted receptacle with corrugated walls containing such source, means for causing a

fluid to trickle down over the corrugations in the zone of the rays, and means comprising an electro-magnet in the circuit of the source of the rays for holding the receptacle in operative position when the lamp is energized, and to automatically release the receptacle when the circuit is cut off. 65

2. An apparatus for sterilizing fluid by exposure to ultra-violet rays, comprising, in combination, a source of ultra-violet rays which requires to be tilted for starting it in operation, a pivoted receptacle containing said source, means for passing a fluid through the receptacle in the zone of the rays, and an electro-magnet in the circuit of the source of the rays, for holding, while energized by the current, the receptacle in operative position and for automatically releasing the same when the current is interrupted. 70 75

3. An apparatus for sterilizing fluids by exposure to ultra-violet rays, comprising in combination a source of ultra-violet rays, a pivoted receptacle with corrugated walls containing the said source, means for causing a fluid to trickle down over the corrugations in the zone of the rays, and an electro-magnet in the circuit of the source of the rays, for holding the receptacle in position. 80 90

4. An apparatus for sterilizing fluids by exposure to ultra-violet rays, comprising in combination a source of ultra-violet rays, a pivoted receptacle with corrugated walls containing the said source, means for causing a fluid to trickle down over the corrugations in the zone of such rays, and an overflow-outlet in the base of the receptacle which discharges the contents of the same when the receptacle is tilted. 95 100

5. An apparatus for sterilizing fluids by exposure to ultra-violet rays, comprising in combination a pivoted receptacle through which the fluid is adapted to flow, provided with an inlet and an outlet for said fluid, a trap at the bottom of the receptacle for containing a quantity of the fluid while the receptacle is in operative position, and a source of ultra-violet rays located in said receptacle, consisting of a mercury vapor lamp, a portion of which is submerged in the fluid contained in the trap, the trap being also provided with an outlet for discharging the fluid therefrom when the receptacle is turned to inoperative position. 110 115

6. An apparatus for sterilizing fluid by exposure to ultra-violet rays, comprising, in combination, a source of ultra-violet rays, a pivoted receptacle containing said source, means for passing a fluid through the receptacle in the zone of the rays, and an electro-magnet in the circuit of the source of rays for holding, while energized by the current, the receptacle in operative posi- 120 125

tion and for automatically releasing the same when the current is interrupted.

7. An apparatus for sterilizing fluids by exposure to ultra-violet rays, comprising in combination a pivoted receptacle provided with an inlet and an outlet for the passage of fluid therethrough, a source of ultra-violet rays contained in said receptacle, and through the zone of whose rays the fluid passes, and an additional outlet through

which fluid trapped in the bottom of the receptacle passes when the latter is turned to inoperative position.

In testimony whereof I affix my signature in the presence of two subscribing witnesses. 15
